BELT SANDER

Fred L. Gordo, Los Angeles, and John G. Stinde, Lawndale, Calif.

Application July 13, 1953, Serial No. 367,640

5 Claims. (Cl. 51—135)

Our invention relates to belt sanders, and included in the objects of our invention are:

First, to provide a belt sander which is so arranged as to be mounted directly upon an electric motor, thereby to reduce to a minimum the number of parts required and to simplify in general the construction of the belt sander.

Second, to provide a belt sander of this type which may be incorporated with various sizes and styles of electric motors irrespective of the normal direction of rotation of the motor shaft.

Third, to provide a belt sander of this type which, though extremely simple of construction, incorporates a tilting table and backing member to permit surface sanding operations, and which may be arranged for contour sanding if desired.

Fourth, to provide a sander of this type which may accommodate sanding belts of different lengths and which incorporates a simple, yet effective means of maintaining proper sanding belt tension.

Other objects and advantages of this invention will be apparent from the following detailed description of the preferred embodiment thereof as illustrated in the accompanying drawings in which:

Figure 1 is a front view of our belt sander.

Figure 2 is a side view thereof.

Figure 3 is a fragmentary side view of the idler pulley and associated mechanism viewed from the opposite side from Figure 2.

Figure 4 is a transverse sectional view through 4—4 of Figure 1.

Figure 5 is a fragmentary enlarged sectional view through 5—5 of Figure 1 with the drive motor omitted.

Our belt sander is adapted to be mounted directly upon an electric motor 1 so that the electric motor not only forms a drive means for the sander, but also a support therefor. Virtually any electric motor having a rating from one-sixth to a one-half horsepower or greater may be used.

Our belt sander includes a channel member 2 adapted to rest on top of the electric motor and be secured thereto by four rods 3 which are secured in the flanges of the channel member and terminate in lugs which receive the ends of a pair of U-bolts 4 extended around the motor 1 adjacent its ends. A series of holes may be provided in the flanges of the channel member so that the channel member may be secured to various sizes and styles of electric motors.

One end of the channel member 2 is provided with a boss 5 having a horizontal bore which receives the horizontal end 6 of a post 7. The post 7 extends rearwardly from the boss 5 and is bent into an open loop 8 in order to curve upwardly and terminate in a vertically directed end 9. The vertical end 9 of the post 7 receives a pair of spaced collars 10 which may be secured to the post by set screws. The collars 10 are provided with rearwardly directed lugs which are joined by a connecting bar 11.

Slidably mounted on the post between the collars 10

2

is a bracket 12 which is provided with a yoke 12a straddling the connecting bar 11 to prevent rotation of the bracket about the vertical axis of the post. A spring 13 is interposed between the bracket 12 and the lowermost 5 collar 10. The bracket 12 projects forwardly from the post and is provided with a horizontal bearing having a laterally directed shaft 14 which carries an idler pulley 15. The position of the post 7 and bracket 12 is such that the idler pulley 15 is disposed above the shaft 16 of the electric motor 1. Secured to the shaft 16 is a drive pulley 17. Wrapped about the drive pulley 17 and idler pulley 15 and extending vertically therebetween is a sanding belt 18.

A work table 19 is mounted in front of the belt 18 and is provided with a notch or slot 20 which receives the forward reach of the belt 18. The mounting table is provided with a pair of mounting lugs 21, either one of which may be disposed so as to overlie one side of the boss 5 and be secured thereto by a screw 22.

Each mounting lug 21 is slotted so that the worktable may be adjusted between a horizontal position and an angular position as indicated by dotted lines in Figure 5.

It will be observed that the plane passing through the axes of the idler pulley and drive pulley are substantially centered with respect to the channel member 2. The post 7 may be inserted in either direction into the boss 5 and the worktable may be secured by one lug or the other to either end of the boss. By this arrangement of the parts the belt sander may be arranged so as to be driven by either a clockwise rotating or a counterclockwise rotating motor shaft.

In order that the worktable may be interchanged and the post 7 securely fastened, three set screw openings are provided in the boss 5. Either end set screw opening may accommodate the set screw 22. The other two openings may receive set screws 23 which secure the post 7.

It is desirable for some sanding operations to provide a backing member disposed behind the operating reach of the belt sander. For this purpose a backing member 24 is provided which is in the form of an L-shaped plate having a vertical leg located behind the operating reach of the belt within the slot 20 of the worktable and a horizontal leg which is secured to a flange of the channel member 2 below the boss 5 by means of a screw 25.

It will be observed that while the member 18 is referred to as a "belt sander", other cutting or abrading tools in belt form may be carried by the pulleys.

It also will be observed that by reason of the arrangement of the collars 10, various lengths of belts may be accommodated and that the spring 13 may be arranged to apply the desired tension.

Having fully described our invention, it is to be understood that we do not wish to be limited to the details herein set forth, but our invention is of the full scope of the appended claims.

We claim:

1. A belt driving mechanism, comprising: a channel-shaped base member adapted to be mounted on the case of an electric motor; fastening means encircling the case of the motor for rigidly securing said base member thereon; said base member having a bored boss across one end in a plane traversing the shaft of said motor; a post having a horizontal end fitting said boss, said post extending rearwardly from said boss, then curving upwardly and forwardly and then extending vertically; said post defining a plane perpendicular to and traversing said base member, an idler pulley supported from the vertical portion of said post; a drive pulley adapted to mount on the shaft of said electric motor; a belt device connecting said pulleys; a work table tiltably supported from said base member and disposed forwardly of the forward reach of said belt

device; and a backing member supported from said base member and disposed behind the forward reach of said belt device in the vicinity of said table.

2. A belt driving mechanism, comprising: a channel-shaped base member adapted to be mounted on the case of an electric motor; fastening means encircling the case of the motor for rigidly securing said base member thereon; said base member having a bored boss across one end in a plane traversing the shaft of said motor; a post having a horizontal end fitting said boss, said post extending rearwardly from said boss, then curving upwardly and forwardly and then extending vertically; said post defining a plane perpendicular to and traversing said base member, a bracket slidably mounted on the vertical portion of said post; a spring urging said bracket upwardly on said post; a guide bar adjustably mounted at one side of said post and restraining said bracket against rotation about the axis of said post; an idler pulley carried by said bracket; a drive pulley adapted to mount on the shaft of said electric motor; and a belt device connecting said pulleys.

3. A belt driving mechanism, comprising: a channel-shaped base member adapted to be mounted on the case of an electric motor; fastening means encircling the case of the motor for rigidly securing said base member thereon; said base member having a bored boss across one end in a plane traversing the shaft of said motor; a post having a horizontal end fitting said boss, said post extending rearwardly from said boss, then curving upwardly and forwardly and then extending vertically; said post defining a plane perpendicular to and traversing said base member, a bracket slidably mounted on the vertical portion of said post; a spring urging said bracket upwardly on said post; a guide bar adjustably mounted at one side of said post and restraining said bracket against rotation about the axis of said post; an idler pulley carried by said bracket; a drive pulley adapted to mount on the shaft of said electric motor; a belt device connecting said pulleys; and a work table tiltably supported from said base member and disposed forwardly of the forward reach of said belt device.

4. A belt driving mechanism, comprising: a channel-shaped base member adapted to be mounted on the case of an electric motor; fastening means encircling the case of the motor for rigidly securing said base member thereon; said base member having a bored boss across one end in a plane traversing the shaft of said motor; a post having a horizontal end fitting said boss, said post extending rearwardly from said boss, then curving upwardly and

forwardly and then extending vertically; said post defining a plane perpendicular to and traversing said base member, a bracket slidably mounted on the vertical portion of said post; a spring urging said bracket upwardly on said post;

5. a guide bar adjustably mounted at one side of said post and restraining said bracket against rotation about the axis of said post; an idler pulley carried by said bracket; a drive pulley adapted to mount on the shaft of said electric motor; a belt device connecting said pulleys; a work table tiltably supported from said base member and disposed forwardly of the forward reach of said belt device; and a backing member supported from said base member and disposed behind the forward reach of said belt device in the vicinity of said table.

10 15. 5. A belt driving mechanism adapted for installation on an electric motor wherein the motor case forms a mounting stand; a base member adapted to rest on the case of an electric motor and having an upper surface extending parallel with the axis of the motor shaft; straps

20 extending from said base member and encircling said motor to secure said base member thereon; a boss at one end of said base member having a horizontal bore traversing said motor shaft; a post including a horizontal portion fitting the bore of said boss, said post extending rear-

25 wardly then forwardly and vertically to form an idler pulley support above said boss; an idler pulley mounted on said pulley support; a drive pulley mounted on said motor shaft; a belt extending between said pulleys forming a forward reach and a rearward reach, a belt backing

30 bracket extending from said base member behind the forward reach of said belt; and a work table pivotally connected to said boss and disposed forwardly of said forward reach.
